UNITED STATES PATENT OFFICE.

DAVID E. ROSS, OF LAFAYETTE, INDIANA.

INTERNAL-COMBUSTION ENGINE.

Application filed April 13, 1921. Serial No. 461,011.

This invention is an improvement in internal combustion engines and the principal object of the invention is to produce an engine in which a high compression ignition cylinder of the Diesel type is combined with a low compression working cylinder; compressing air in the compression cylinder to from 600 to 2500 pounds (thereby superheating the air far above the ignition point of any fuel element) while the compression in the main or working cylinder can be about 80 pounds or less.

Another object is to introduce fuel into the compression cylinder, preferably liquid hydrocarbon, and mix it with the air and produce a highly compressed explosive mixture which will be ignited by reason of the superheated mixture produced in the compression cylinder, and discharged while burning into the working cylinder. In other words to compress an explosive mixture in the compression cylinder to such a high degree that the temperature thereof will be far above the igniting point of the fuel element that all the fuel elements therein will be ignited, and then discharge the mixture, while burning, into the working cylinder at a pressure which will be above the ignition point of any fuel in the working cylinder thereby insuring ignition of the mixture in the working cylinder (if there be any mixture therein) and enabling the usual carburetors and usual ignition devices to be dispensed with; or a carburetor may be used to produce the mixture in the low compression cylinder, in which case the high compression cylinder can be employed for ignition only. By discharging such a highly compressed superheated burning mixture into the working cylinder I insure absolute practical instantaneous ignition and complete combustion of all the fuel elements in the working cylinder, and obtain high efficiency of the working cylinder.

Another object of the invention is to provide a supply of fuel in a pocket or chamber between the compression cylinder and the working cylinder, which is discharged by and with the compressed highly heated air or burning mixture into the working cylinder, such burning mixture picking up and igniting the fuel in the pocket and discharging the same burning into the working cylinder, thus insuring that every fuel element shall be ignited and consumed in the working cylinder with resultant high efficiency.

By providing such fuel pocket and discharging the fuel therefrom into the working cylinder any mixture therein will be ignited by the superheated highly compressed air or mixture passing from the compression cylinder into the working cylinder. When thus operated the superheated compressed air or burning mixture issuing from the compression cylinder sweeps up and atomizes the fuel in the pocket and discharges it into the working cylinder. In such cases I could dispense with the introduction of fuel from any other source into the working cylinder, and only use the latter to compress sufficient air to insure the complete oxidation of all the fuel elements discharged into the working chamber by the highly compressed heated air or burning mixture passing from the compression chamber into and through the pocket and into the working cylinder.

With this invention a very high pressure is generated in the compression chamber and a very low pressure can be used in the working cylinder and in each instance the fuel or air discharged to the working cylinder is superheated far above the point of ignition of any fuel element, therefore the engine can be operated without any supplementary ignition devices and without using any carburetor, thus producing an engine of most efficient, simple and novel construction.

I will explain one practical embodiment of the invention as illustrated in the accompanying drawings to enable others to clearly understand and use the invention; but I do not consider the invention restricted to any particular make or construction of engine, and therefore refer to the claims for summaries of the essentials of the invention and novel features of construction and combination of parts for which protection is desired.

In said drawings:

Fig. 1 is a longitudinal vertical sectional elevation of a complete engine embodying the invention.

Fig. 2 is a transverse vertical section thereof.

Fig. 3 is an enlarged detail sectional view showing the positions of the parts at the moment of discharge of the highly compressed superheated ignition gases from the compression cylinder through the fuel pocket into the working cylinder.

Fig. 4 is a similar view showing the posi-

tion of the parts on the intake stroke of the cylinders.

The engine shown in the drawings has a working cylinder 1 in which is a piston 1^a connected by a pitman 1^b to a crank 2^a on the main shaft 2. This working cylinder is provided at its upper end with the usual inlet and outlet valves 1^c and 1^d, which may be operated by any suitable mechanism from the main shaft 2, as indicated in the drawings, but as the particular mechanism for operating the valves forms no part of the present invention it is not necessary to further describe the same herein. The inlet valve 1^c controls the inlet of fuel from the passage 1^{ex} which may be connected to any suitable fuel supply in the usual manner.

Beside the working cylinder 1 is a compression cylinder 3 in which is a piston 3^a connected by a pitman 3^b to a crank or eccentric 2^b on the main shaft 2; so arranged that the pistons 3^a and 1^a are operated in proper times as in a Diesel engine.

The cylinder 3 is provided with an inlet port which is closable by a valve 4 having a stem 4^a which projects through the head of the cylinder casing and is held normally closed in the example shown by means of a spring 4^b, but may be opened by means of a lever 4^d that is adapted to be depressed at the proper time by suitable means, and may be operated simultaneously with and by the same means that operates the inlet valve 1^c of the working cylinder, so as to admit air into the compression cylinder on the down stroke of the piston therein, at the same time that air is admitted into the working cylinder on the down stroke of the piston therein. In the form of construction illustrated the valve stem 4^a has a central air passage 4^s which opens to the atmosphere adjacent the upper end of the stem, and has an outlet 4^t in the side of the valve 4, which outlet is closed when the valve 4 is seated as in Fig. 3.

Fuel (such as kerosene or liquid hydrocarbon) can be admitted into the compression cylinder 3 through a duct 5, the inner end of which preferably opens into the seat of the valve 4 so that the fuel inlet is also opened and closed by the valve 4. Thus when the valve 4 is opened the air entering the cylinder from port 4^t passes the inlet of duct 5 and the suction tends to draw oil therethrough into the compression cylinder and the air disperses and mixes with the oil in the cylinder. The amount of oil supplied to duct 5 is controlled by an adjustable valve 5^a of any suitable type; and oil may be supplied to the valve chamber above duct 5 through an opening 5^b connected with any suitable oil supply (not shown).

An explosive mixture of oil and air will be drawn into the compression cylinder 3 on the down stroke of the piston 3^a; and on the

upstroke of piston 3^a this mixture will be compressed to such an extent that the mixture will be superheated to a temperature far above the igniting point of the fuel elements and the fuel will be ignited and when this highly compressed superheated burning mixture is admitted into the working cylinder it will instantaneously ignite the fuel elements in the working cylinder and insure thorough combustion of the explosive mixture in the working cylinder.

Owing to its high compression and superheat, the air or fuel mixture in the compression cylinder will ignite when discharged into the working cylinder and no auxiliary electrical or hot point ignition devices whatsoever are required, neither is any carburetor required with this method of operation; however I prefer to admit fuel into the working cylinder, as not enough explosive mixture could ordinarily be supplied by the compression cylinder to effectively operate the engine under load, although it would operate it if running idle.

Fuel might be supplied to the working cylinder by any ordinary means, but instead of admitting the necessary amount of fuel into the working cylinder I preferably provide a fuel pocket or chamber intermediate the compression cylinder and the working cylinder. As shown a fuel poscket 6 is provided preferably in the engine casting (as indicated in Figs. 1, 3 and 4) and fuel is supplied to this pocket 6 from the chamber of valve 5^a.

As shown in Figs. 3 and 4, a valve chamber 7 is provided in the casting above the chamber 6, and this valve chamber is formed by an upper member 7^a, and a lower member 7^b, which may be screwed into a threaded opening in the casting—see Fig. 3. The members 7^a, 7^b are provided with axial apertures or ports and on their opposed faces with valve seats respectively adapted to be engaged alternately by a double valve 8 attached to a valve rod 8^a which extends upwardly through a sleeve 9 fitted in a bore in the casting above the valve chamber 7. This sleeve 9 has its lower end reduced leaving an annular chamber 9^a above the valve chamber 7 adapted to communicate with this chamber when the valve 8 is on the lower seat. The sleeve 9 may be tapped into the bore in the casting as indicated so that it can be adjusted so as to regulate the size of the chamber 9^a.

The chamber 9^a communicates with the chamber of valve 5^a by means of a duct 6^a, which intersects the passage of the valve stem 4^a and this stem is annularly grooved as at 4^e so that the proper supply of fuel to the chamber 9^a will not be hindered.

The rod 8^a extends through the sleeve 9 and is provided with a collar 8^b on its upper end, and a spring 8^c interposed between the collar and the upper end of the sleeve 9 and

normally holds the rod 8^a lifted and the valve 8 seated against the upper seat in part 7^a in the valve chamber 7, thus closing communication between the chamber 9^a and the 5 valve chamber 7.

The valve rod 8^a may be depressed at the proper times by the same devices that depress the valve 4. As shown a spring plate 8^b is connected to the upper end of rod 8^a, 10 and contacts with the under side of lever 4^a, so that when the valve 4 is opened valve stem 8^a will be yieldingly depressed so as to open the upper port in the chamber 7 and close the lower port in this chamber; so that while 15 the valve 4 is open on the intake stroke of the piston 3^a oil will flow from the chamber 9^a into the valve chamber 7 but cannot pass into the pocket 6. When the valve 4 closes, valve 8 is raised by the action of the spring 20 8^b and opens the lower port in valve 7 and closes the upper port therein; and in so doing permits the desired quantity of oil to pass from the chamber 9^a into the valve chamber 7 and from the latter chamber into 25 the pocket 6.

In the example shown the amount of fuel supplied to pocket 6 can be regulated by adjusting the size of the chamber 7. The pocket 6 can be supplied with the proper 30 amount of fuel by any other suitable means, and the compression cylinder may be supplied with air and oil by any other suitable means and I do not consider the invention limited to the particular devices for such 35 purposes illustrated in the drawings.

The pocket 6 communicates with the upper end of the working cylinder by means of a port 6^b and it has a port 6^c which opens into the compression cylinder 3 at a point which 40 will be below the upper end of the piston 3^a when the latter is in its lowermost position.

The piston 3^a is provided with a port 3^e which opens through its upper end, and also through its side at such a point that the 45 lower end of this port 3^e registers with the port 6^c just as the piston reaches the limit of its upper stroke (Fig. 3) so that the highly compressed air or highly compressed mixture in the compression cylinder 3 will 50 be at that time discharged through the ports 3^e and 6^c into the pocket 6 and thence through port 6^b into the working cylinder.

When such highly compressed superheated burning mixture is discharged from the 55 compression cylinder into the pocket it picks up and ignites the fuel in the pocket and discharges it under high pressure and at a high temperature and burning into the working cylinder wherein the fuel elements are all 60 consumed and utilized in effectively operating the working piston.

With this construction and method of 65 operation when the parts are properly adjusted the working cylinder can be operated under ordinary working conditions without

other admission of fuel thereto. Of course if desired additional fuel may be admitted into the working cylinder by any ordinary means to produce a richer explosive burning therein. The burning mixture therein 70 can be made richer or poorer by varying the amount of fuel supplied to the working cylinder from the pocket.

Operation.

75

On the admission or down stroke valve 4 is opened preferably simultaneously with valve 1^c; and valve 8 is depressed so as to close the lower port of chamber 7 and open the upper port thereof. Fuel oil then flows 80 through duct 5 into the compression cylinder 3 and through duct 6^a and chamber 9^a into the chamber 7, the larger quantity of fuel going into the chamber 7. At the beginning of the compression or up stroke of 85 the pistons valve 4 closes and valve 8 rises opening the lower port in chamber 7 and closing the upper port thereof and the fuel oil in chamber 7 flows into the pocket 6.

During the compression stroke of the pistons the air or mixture is compressed in cylinder 1 by piston 1^a to a temperature of about 350 degrees F. and the air or mixture is compressed in cylinder 3 by piston 3^a until it reaches a temperature of about 1100 degrees F. This intense heat vaporizes a portion of the fuel in the compression cylinder and ignites the vapor near the end of the compression stroke and causes a burning expansion (when port 3^e registers with port 6^c). The expanding burning gases pass through the ports 3^e, 6^c into pocket 6, and ignite the fuel in this pocket and spray it through ports 6^b into the working cylinder 1 where all the fuel elements admitted 100 thereto are ignited and the resultant expansion of the gases drives the piston 1^a on its power stroke. 105

By supplying extra fuel to the highly compressed air or mixture between the compression cylinder and the working cylinder such extra fuel can be atomized, superheated and discharged combusting into the working cylinder; and the fuel discharged into the working cylinder being heated far above the 110 point of ignition and combustion, insures thorough combustion of all of the fuel particles in the working cylinder. This enables me to operate the working cylinder with nothing but air compressed therein on the 115 compression stroke; or with only a very weak mixture compressed therein; according to the amount of fuel supplied to the pocket. The amount of superheated fuel mixture supplied to the working cylinder can be 120 varied according to the amount of fuel supplied to the cylinder from the pocket.

In each instance the air and fuel discharged into the working cylinder from the compression cylinder is superheated far be- 125

yond the point of ignition, and the fuel atoms are ready for instantaneous oxidization by the air in the working cylinder; and also any fuel elements in the working cylinder will be instantly ignited, and practically all the fuel elements in the working cylinder will be simultaneously ignited; and the most thorough combustion and consequent most effective and economical operation insured.

An engine constructed and operated as described would be highly efficient, very economical in fuel, does not require any auxiliary ignition devices, such as electrical igniters, hot points, etc. and does not necessarily require any carburetor. Such an engine can be operated on very low grades of hydrocarbon oils and might even be operated with finely powdered carbonaceous fuel, as the highly compressed superheated air or mixture produced in the compression cylinder being heated far above the ignition point of the fuel will when discharged into the working cylinder instantaneously ignite all the fuel atoms and insure complete oxidization thereof.

What I claim is:

1. In an internal combustion engine, the combination of a working cylinder; a compression cylinder; a valve for admitting a charge into the working cylinder; a valve for admitting air into the compression cylinder; means for operating the second mentioned valve by and with the first mentioned valve; a piston in the compression cylinder adapted to compress the air therein until its temperature is raised above the ignition point of the fuel; a piston in the working cylinder adapted to compress the charge therein to a point below the ignition point of the fuel; and means for discharging the superheated air from the compression cylinder into the working cylinder.

2. In an engine as set forth in claim 1, said compression cylinder having a bore; a stem for said second valve extending through the bore; and an air passage extending through the stem and terminating in the side of said valve, whereby when the valve is closed the air passage will be closed.

3. In an engine as set forth in claim 1; said means for operating the second mentioned valve, comprising a depressible lever engaging the stem of said second valve, and connections between the stem of said first mentioned valve and said lever whereby both valves will be operated simultaneously.

4. In an internal combustion engine, the combination of a working cylinder, a compression cylinder; a valve for admitting air into the working cylinder on the intake stroke thereof; a valve for admitting air into the compression cylinder on the intake stroke thereof; means for operating the second mentioned valve by and with the first

valve; a piston in the compression cylinder adapted to compress the air therein until its temperature is raised above the ignition point of the fuel; a piston in the working cylinder adapted to compress the air therein to a point below the ignition point of the fuel; means for providing a liquid fuel charge intermediate the cylinders; and means for discharging the superheated air from the compression cylinder through the charge and into the working cylinder.

5. In an engine as set forth in claim 4, said compression cylinder having a bore; a stem for said second valve extending through the bore; and an air passage extending through the stem communicating with the atmosphere and terminating in the side of said valve, whereby when the valve is closed the air passage will be closed.

6. In an engine as set forth in claim 4; said means for operating the second mentioned valve comprising a depressible lever engaging the stem of said second valve, and connections between the stem of said first mentioned valve and said lever, whereby both valves will be operated simultaneously.

7. In an engine as set forth in claim 4, said fuel providing means comprising a duct connecting said cylinders; a fuel pocket in said duct; a bore communicating with said pocket; a valve stem in said bore; a pair of spaced opposed valve seats in the bore adjacent the pocket; a double valve mounted upon the stem intermediate the valve seats; means for feeding fuel into the bore adjacent the valve seats; and means for operating said last mentioned valve.

8. In an engine as set forth in claim 4, said fuel providing means comprising a duct connecting said cylinders; a fuel pocket in said duct; a bore in the engine casing communicating with said fuel pocket; a sleeve adjustably mounted in said bore; a valve stem mounted in said sleeve; a pair of spaced opposed valve seats in the bore adjacent the fuel pocket; a double valve mounted upon the stem intermediate the valve seats; a feed duct communicating with the fuel chamber; and means for operating said last mentioned valve.

9. In an internal combustion engine, the combination of a working cylinder, a compression cylinder; a valve for admitting air into the working cylinder on the intake stroke thereof; a valve for admitting air into the compression cylinder on the intake stroke thereof; a piston in the compression cylinder adapted to compress the air therein until its temperature is raised above the ignition point of the fuel; a piston in the working cylinder adapted to compress the air therein to a point below the ignition point of the fuel; a duct connecting said cylinders, a fuel pocket in said duct; a bore extending through the engine casing and

- communicating with said pocket; a valve stem in said bore; a pair of spaced opposed valve seats in the bore adjacent the pocket; a double valve on the stem intermediate the seats; means for feeding fuel into the bore; means for operating the double valve by and with the first mentioned valve; and means for discharging the superheated air from the compression cylinder through the fuel pocket and into the working cylinder on the firing stroke.
10. In an engine as set forth in claim 9; said means for operating the double valve comprising a depressible lever engaging the stem of said second valve, and connections between the stem of said first mentioned valve and said lever, whereby both valves will be operated simultaneously.
11. In an engine as set forth in claim 9, means for regulating the amount of fuel supplied to said pocket, comprising a sleeve adjustably mounted in the bore; and said double valve stem extending through said sleeve.
12. In an engine as set forth in claim 4; said compression cylinder have a valve seat
- therein for said second valve and having a bore therein registering with said seat; a stem for said valve extending through the bore; an air passage extending through the stem and terminating in the side of said valve; a fuel duct opening into the valve seat; whereby when the valve is closed the supply of air and fuel will be cut off.
13. In an engine as set forth in claim 4, 35 said compression cylinder having a valve seat therein for said second valve; and having a bore registering with said seat; a stem for said valve extending through the bore; an air passage extending through the stem 40 and communicating with the atmosphere, the inner end of said passage terminating in the side of said second valve; a fuel duct opening into the valve seat; means for controlling the amount of fuel passing through said duct; the inner end of the fuel duct being adjacent the inner end of the air passage, whereby when the valve is opened the air will spray the fuel into the cylinder.
14. In testimony that I claim the foregoing as 50 my own, I affix my signature.

DAVID E. ROSS.
